E. R. BURTNETT

INTERNAL COMBUSTION ENGINE

Filed July 26, 1923

Inventor:
Everett R. Burtnett
By Martin P. Smith, Atty.

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed July 26, 1923. Serial No. 653,889.

My invention relates generally to internal combustion engines and more particularly to the construction of the ignition and combustion chambers for charge stratification types of engines.

The principal object of my invention is, to provide, in an internal combustion engine operating on the two stroke cycle principle and having an L-head type inlet valve and ignition chamber, a substantially goose neck shaped chamber that provides a connection and passageway between the ignition chamber and the piston chamber, said goose neck chamber being tapered or of gradually increasing diameter from the ignition chamber to the piston chamber, so as to obtain a more perfect stratification of the residual and fresh gaseous fuel charged taken into said chamber and which result is attained with less wall area to a given amount of cubic content and consequently effecting a relatively higher degree of thermal efficiency in the operation of the engine.

A further object of my invention is to provide, in an engine of the character referred to, a single valve that opens into a substantially globular ignition chamber, said valve and chamber having axes that are substantially coincident with each other and parallel with the axis of the piston chamber and, further, to provide the engine with a readily removable head structure, so as to permit of the ready insertion or removal of the valve and give ready access to the combustion, goose neck and piston chambers.

With the foregoing and other objects in view, my invention consists in certain novel features of construction and arrangement of parts that will be hereinafter more fully described and claimed and illustrated in the accompanying drawings, in which:—

The figure is a vertical section taken lengthwise through the center of an engine cylinder of my improved construction.

Referring by numerals to the accompanying drawings, 10 designates a cylinder, within which is arranged for operation a piston 11.

Formed through the wall of this cylinder intermediate its ends is an exhaust port 12 that is uncovered only when piston 11 is at the outer or lower end of its stroke.

The upper portion of the cylinder wall

has formed thereon, heat-radiating fins 13 and formed integral with the upper portion 55 of said cylinder and to the side thereof is a housing 14, in the lower portion of which is formed a gaseous fuel inlet port 15.

Formed in the upper portion of the housing 14 is a substantially flat globular ignition chamber 16 and seated in the wall of said housing to side of said chamber is a spark plug 17, the terminals of the electrodes of which project into said ignition chamber.

Formed on the shoulder around an opening 18 that establishes communication between inlet port 15 and ignition chamber 16 is a seat for a spring held poppet valve 19, that may be unseated by means of the conventional cam or rocker arm (not shown).

The head 20 for the cylinder 10 and housing 14 is a substantially flat, dome shaped member, preferably cast and having integral, externally arranged, heat radiating fins 21.

This head fits snugly upon and is detachably secured in any suitable manner, to the upper ends of cylinder 10 and housing 14 and formed within said head is a substantially goose neck shaped chamber 22, the internal diameter of which gradually increases from one end to the other, and said chamber being disposed so that its smaller and larger ends communicate respectively with the upper ends of the ignition chamber 16 and the piston chamber.

This chamber 22 in addition to serving as a connecting chamber of gradually increasing diameter from the combustion chamber to the piston chamber, functions as a compressed charge stratification chamber and a gaseous fuel charge combustion chamber.

At the termination of each out or down stroke of the piston 11, port 12 is uncovered to permit the greater portion of the products of combustion to exhaust from the piston chamber and this exhaust or scavenging action is materially assisted by the inrush of gaseous fuel that is admitted under pressure through inlet ports 15 and 18 while valve 19 is open.

As the piston travels upward or inward in its chamber, the admitted gaseous fuel charge and residual products of combustion will be compressed in stratified relation within ignition chamber 16 and tapered chamber 22, with a stratum of gaseous fuel compressed

within said chamber 16 and in the smaller end of chamber 22 and with a stratum of residual products of combustion compressed within the larger end and intermediate portion of said chamber 22.

At the point of highest compression and as piston 11 passes high center or immediately thereafter, a spark is produced between the terminals of the electrodes of spark plug 17 thereby igniting the compressed gaseous fuel charge within chamber 16 and the flame propagation and the expansion resulting from combustion, will pass through chamber 22 and be directed against the head of the piston to drive same downward on its power stroke.

Inasmuch as the tapered chamber is comparatively short, the wall and surrounding said chamber is minimized in proportion to 20 the total cubic content of the chamber 22 and this provision materially increases thermal efficiency in operation.

Thus it will be seen that I have produced an internal combustion engine that is of 25 relatively simple structure, capable of being easily and cheaply produced and which will be effective in materially increasing the production of power.

Obviously, minor changes in the size, 30 form and construction of the various parts of my improved internal combustion engine may be made and substituted for those herein shown and described without departing from the spirit of my invention, the scope of which is set forth in the appended 35 claims.

I claim as my invention:

1. In an internal combustion engine, the combination with a cylinder provided with 40 a piston chamber and a separately formed flat globular combustion chamber, the diameter of the latter being less than the diameter of the piston chamber and there being a valved inlet port into the lower end 45 of said combustion chamber and the diameter of which port is substantially less than that of the intermediate portion of said flat globular combustion chamber, of a one-piece head block applied to the head end of the 50 cylinder and closing said piston chamber and combustion chamber, there being a goose neck chamber formed in said head block and connecting the head end of the piston chamber with the upper end of the combustion 55 chamber and which goose neck chamber gradually increases in size from the end that communicates with the combustion chamber

to the end that connects with the piston chamber.

2. In an internal combustion engine, the combination with a cylinder provided with a piston chamber and a separately formed flat globular combustion chamber, the diameter of the latter being less than the diameter of the piston chamber and there being a valved 60 inlet port into the lower end of said combustion chamber and the diameter of which port is substantially less than that of the intermediate portion of said flat globular combustion chamber, of a one-piece head block applied 65 to the head end of the cylinder and closing said piston chamber and combustion chamber, there being a goose neck chamber formed in said head block and connecting the head end of the piston chamber with the 70 upper end of the combustion chamber, said goose neck chamber gradually tapering in cross sectional dimensions throughout its length with its larger end connected to and having the same diameter as the head end 75 of the piston chamber in the cylinder and the smaller end of said goose neck chamber being connected to the upper end of the combustion chamber.

3. In an internal combustion engine, the combination with a cylinder provided with a piston chamber and a separately formed flat globular combustion chamber, the diameter of the latter being less than the diameter of the piston chamber and there being a valved 80 inlet port into the lower end of said combustion chamber and the diameter of which port is substantially less than that of the intermediate portion of said flat globular combustion chamber, of a one-piece head block applied 85 to the head end of the cylinder and closing said piston chamber and combustion chamber, there being a goose neck chamber formed in said head block and connecting the head end of the piston chamber with the 90 upper end of the combustion chamber, said goose neck chamber gradually tapering in cross sectional dimensions throughout its length with its larger end connected to and having the same diameter as the head end of 95 the piston chamber in the cylinder, the smaller end of said goose neck chamber being connected to the upper end of the combustion chamber and heat radiating fins formed on the external surface of the head 100 block.

In testimony whereof I affix my signature.

EVERETT R. BURTNELL.
